FOREIGN PATENT DOCUMENTS

WO 2004/076604 A2 9/2004

Primary Examiner — Rhea Shields(74) *Attorney, Agent, or Firm* — Standley Law Group LLP; Adam J. Smith; Jeffrey S. Standley(57) **CLAIM**

The ornamental design for a hospital cart, as shown.

DESCRIPTION

FIG. 1 is a front perspective view of the hospital cart; FIG. 2 is a front elevation view of the FIG. 1 device; FIG. 3 is a rear elevation view of the FIG. 1 device; FIG. 4 is a right side elevation view of the FIG. 1 device; FIG. 5 is a left side elevation view of the FIG. 1 device; FIG. 6 is a top plan view of the FIG. 1 device; FIG. 7 is a bottom plan view of the FIG. 1 device; and, FIG. 8 is a rear perspective view of the FIG. 1 device. In the drawings, the broken lines are for the purpose of illustrating environment only and form no part of the claimed design.
